SOCK STRETCHER

Bruce A. Gear, Los Angeles, Calif.

Application September 12, 1945, Serial No. 615,857

12 Claims. (Cl. 223—75)

1

This invention relates to stretchers for socks and stockings, to be used in preserving the size and shape of a sock or stocking while it is drying after having been washed.

An object of the invention is to provide a sock or stocking stretcher arranged to operate in a novel and extremely simple manner. The invention contemplates the use of a form comprising telescoping parts one of which is shaped to fit into the foot of the stock to be stretched and the other of which is shaped to fit into the leg of the sock, together with means for clamping the leg of the sock to the leg part of the form and a screwjack device for extending the leg portion of the form so as to apply tension to the sock.

A further object of the invention is to provide, in a sock stretcher having the characteristics set forth in the preceding paragraph, an extremely simple and quickly operable clamping device for clamping the leg of the sock to the leg of the form.

Another object of the invention is to provide a sock stretcher which may be easily put into the sock and does not have any projecting parts that would catch in the material of the sock. Prior devices have been subject to the objection that they embodied projecting parts that were likely to catch in the material of the sock, interfere with the smooth insertion of the form into the sock, and in some cases tear the sock. The present invention obviates these objectionable features.

Another object of the invention is to provide a sock stretcher embodying a stretching jack that is concealed within the stretching form.

Another object is to provide a sock stretcher that is extremely durable and sturdy in construction.

A further object is to provide a sock stretcher that is pleasing in appearance.

Other objects of the invention will become apparent from the ensuing specification, when read in connection with the accompanying drawing, in which:

Fig. 1 is a side elevation of a sock stretcher embodying the invention;

Fig. 2 is a longitudinal transverse sectional view of the stretcher;

Fig. 3 is a sectional view of the stretcher taken in the plane of the foot portion of the stretching form;

Fig. 4 is an end view of the stretcher;

Fig. 5 is an edge elevation of the stretcher;

Fig. 6 is a transverse sectional view of the foot portion of the stretcher taken on the line 6—6 of Fig. 1.

Fig. 7 is a detailed sectional view of the clamp mechanism taken on the lines 7—7 of Fig. 3;

Fig. 8 is a sectional view of the same detail,

2

parts being broken away and one of the clamps being shown in the raised position;

Fig. 9 is a detailed sectional view of the same taken on the line 9—9 of Fig. 7;

Fig. 10 is a detailed sectional view of a modified form of the clamp mechanism;

Fig. 11 is a horizontal sectional view of the same taken on the line 11—11 of Fig. 10; and

Fig. 12 is a detailed sectional view of another modification of the clamp mechanism.

As an example of one form in which the invention may be embodied, I have shown in the drawing a sock stretcher embodying a two-part, telescoping form having the general outline of the sock to be stretched and including a foot member 12 and a leg member 13. The form members 12 and 13 may be constructed out of any suitable material of adequate thickness and strength, such as cast metal or molded plastic. I prefer to use molded plastic because of the more pleasing appearance that it gives the finished article.

The foot member 12 has cutout apertures 14 therein which facilitates the circulation of air to the foot portion of the sock being stretched and thereby hasten the drying process. The foot member 12 also includes a shank portion 15 over which is telescoped the sleeve portion 16 of the leg member 13. As shown in Fig. 3, the shank portion 15 includes a thickened central rib section 17 and thinner web portions 18 on either side thereof.

The cross-sectional shape of the leg member 13 conforms to this cross-sectional shape of the shank portion 15 having central ridge portions 16' that are raised above the side portions thereof. The thickened rib section 17 is continued at 17' through a major portion of the length of the foot member 12 as shown in Figs. 1 and 6, and the marginal areas of the foot member 12 are in the form of relatively thin webs 18'. Extending along the margins of the apertures 14 are raised beads 19, which assist the ridge portions 16' and rib portions 17' in holding the sock away from the surface of the form and thereby promote the circulation of air through the sock for drying the same. The thickened rib portion 17 accommodates a hole 20 extending longitudinally therein. The side marginal areas of the webs 18' of the foot member 12 and the side marginal areas of the webs 18 of the leg member 13 cooperates to define the periphery of the stretching form. The wall of the sleeve member 16 is tapered gradually to a thin end edge 21 at the inner extremity thereof.

Where the shank member 15 joins the foot member 12, the latter is provided with a laterally thickened ankle region 22 having at its upper extremity a shoulder 22' that extends entirely around the foot member 12 and is substantially flush with the edge 21 of the sleeve 16 so as to

55

55

3

spread the sock and guide it over the edge 21 as the sock is being slipped on to the form. The shoulder 22' may also serve as a stop to limit the retracting movement of the leg member 12 by engagement of the edge 21 thereagainst.

The foot member 12 and leg member 13 are urged apart by a screwjack comprising a screw shaft 23 threaded through a threaded bushing which is pressed into a counterbore 25 in the outer extremity of the hole 20. The screw shaft 23 extends into the hole 20. At its outer end, the screw shaft 23 has an annular flange 26 and a pair of bearing surfaces 27, 28 disposed at either side of the flange. The flange 26 and bearing surfaces 27, 28 are rotatably mounted in a split bushing 29 which is mounted in an opening 30 in the end wall 31 of the leg member 13. The split bushing members 29 have flange members 32 which abut the outer end surface of the end wall 31 and, at their opposite ends, have reduced externally threaded neck portions 34 onto which is threaded a locknut 35.

At this point it may be noted that in assembling the screw shaft 23 in the leg member 13 of the form, the split bushing members 29 are placed in embracing relation to the bearing surfaces 27, 28 and the flange 26, and the assembly of bushing members and shaft is then passed into the opening 30, which confines the bushing sections 29 against spreading. The assembly is then secured in place by tightening the nut 35 on the threaded members 34 within the sleeve 16. The shank member 15, with the threaded bushing 24 installed therein, may then be applied to the end of the shaft 23, and the shaft 23 is then rotated to draw the threaded bushing 24 thereover and to draw the shank member 15 into the sleeve 16.

Rotation of the screw shaft 23 is effected by means of a handle 33 to which is attached the shank end 36 of the shaft 23. This attachment may be accomplished by molding the handle 33 onto the shank end 36.

Carried by the sleeve member 16 are a pair of clamps each comprising a yoke 37 formed of wire and having side arms 38 provided, at their ends, with inwardly extending trunnions 39 and connected by a central region comprising a jaw 40. When the yoke is in a clamping position, the jaw 40 cooperates with a channel 41 in a respective side of the sleeve member 16. The side arms 38 are flattened and knurled to facilitate their being grasped between the fingers, for manipulating the clamps. The trunnions 39 of the respective clamping yokes 38 are received in sockets 42 in the end wall 31 of the leg member 13. The trunnions 39 of one yoke are arranged side by side with the trunnions 39 of the other yoke, and each of these pairs of trunnions is acted upon by spring means which is effective to press the jaws against the channels 41, and when the jaws are open, to hold them open. Merely as an example of one form in which such spring arrangement may be embodied, I have shown in Figs. 7-9 an arrangement wherein the trunnions 39 are each encircled by a spring 43. One end of each spring 43 is attached to the trunnion 39 of one of the yokes. This may be accomplished by bending the ends of the springs 43 inwardly as at 44 and extending the bent ends 44 into openings 45 in the trunnions 39 as shown in Fig. 7. The other end of each spring 43 is attached to a screw 46 that is threaded into the bottom wall of the socket 42. The sides of the screw 46 are flattened as at 47, and the inner

4

ends of the trunnions 39 are flattened as at 48. When the clamps are in their closed positions, the cylindrical surfaces of the trunnions 39 are in engagement with the flats 47 of the screw 46, and the clamps are held snugly in the channels 41 by the tension of the springs 43, tending to uncoil these springs.

With the flats 48 of a clamp yoke 38 engaged against the flats 47 of the screw 46, the yoke 10 will be held in the outstanding position of the upper yoke shown in Fig. 4. This position is also indicated in Fig. 8, in broken lines. The flats are held in engagement with each other by the pull of the coil springs 43 toward the screws 46. This is a lateral pull which is developed as the result of flexing of those portions 49 of springs 43 which extend from the coil portions 50 of the springs to the screw 46.

A modified form of the clamp tensioning means 20 is shown in Fig. 10. In this modification, the trunnions 39a are journaled in the bottom wall 25 of the socket 42a as indicated in Fig. 11, and the intermediate portions of the trunnions 39a are flattened to provide cams 51 that extend radially from the axes of the trunnions 39a as shown in Fig. 10, and engage the inner face of a split ring spring 52. When the cams 49 are in their positions shown in Fig. 10, they will be maintained therein by the embracing pressure of the spring 52, and the clamp yokes will thereby be yieldingly pressed against the channels 41. When the clamp yokes are moved to the position indicated in broken lines at 53, the pressure against the cams 51 will be on center and the clamp yokes 35 will be thereby held in these positions with light restraining force.

In Fig. 12 I have shown a further modification of the clamp tensioning mechanism. In this modification, the trunnions 39b are flat as shown 40 and are each fulcrumed at one edge in an end region 54 of the socket 42b which is in this case oval shaped. The opposite edges of the trunnions 39b are yieldingly engaged by an elliptical spring 55 which is compressed as the jaws are swung 45 from their open positions (shown in Fig. 12) to their closed positions, and vice versa. During such movements the trunnions 39b will pass dead center with reference to the pressure of the spring 55 against them, and consequently they will be 50 yieldingly held either in the open or the closed positions as the case may be. Spring 55 is in the form of an open ellipse, and the central or web portion thereof is adjacent the ends of the trunnions 39b when the jaws are in their 55 closed positions. The pressure against the trunnions in these positions is thus greater than the pressure against the trunnions when the jaws are in the open position. This is desirable, since more spring pressure is required in the closed 60 positions of the jaws than in the open positions thereof.

In using my improved sock stretcher, the sock is first slipped over the foot member 12 and the leg portion of the sock is drawn up over the 65 sleeve 16. With the yokes 38 in their open positions, the open end of the leg portion of the sock is drawn over the channels 41, and the yokes are then sprung inwardly to engage the sock in the channels 41. The handle 33 is then rotated 70 until the slack in the leg portion of the sock is taken up, and the sock may then be permitted to dry.

I claim as my invention:

1. A stretching and drying device for stockings 75 comprising a two-part form including a foot

member and a leg member extensibly connected to each other, means carried by the leg member to clamp the open end portion of a sock to said leg member after the stocking has been drawn over the form; and screwjack means for extending the foot portion from the leg portion so as to take up the slack in the stocking.

2. A stretching and drying device for stockings comprising a two-part form including a foot member and a leg member extensibly connected to each other, means carried by the leg member to clamp the open end portion of a sock to said leg member after the stocking has been drawn over the form, and screwjack means operable when said stocking is thus drawn over the form, to extend the foot portion from the leg portion so as to take up the slack in the stocking.

3. A stretching and drying device for stockings comprising a two-part form including a foot member and a leg member extensibly connected to each other, opposed spring clamps carried by the leg member to clamp the open end portion of a sock to said leg member after the stocking has been drawn over the form; and screwjack means for extending the foot portion from the leg portion so as to take up the slack in the stocking.

4. In a stretching and drying device for stockings, a two-part form including a foot member having a shank and a leg member comprising a sleeve telescoped over said shank; and an end wall at one end of said sleeve; clamp means carried by the end of said leg member for clamping thereto the open end of a stocking that has been drawn over the form; and means extending through said end wall and co-acting with said shank portion of the foot member to extend the foot member away from the leg member and thereby take up the slack in said stocking.

5. In a stretching and drying device for stockings comprising a two-part form including a foot member having a shank portion and a leg member telescopically associated with said shank portion; means for clamping to the end of said leg member remote from said foot member, the open end of a stocking that has been drawn over said form; and means for extending said foot member from said leg member to take up the slack end of said stocking, said last means including a screw shaft extending through said shank portion and leg member longitudinally thereof and a nut threaded upon said screw shaft, and a handle at the outer end of said screw shaft for rotating same.

6. In a stretching and drying device for stockings; a two-part form including a foot member having a shank and a leg member including a sleeve part telescoped over said shank; and an end wall at the outer end of said sleeve; clamp means carried by the end of said leg member and adapted to clamp thereto the open end of a stocking that has been drawn over the form; and a screw shaft extending longitudinally through said end wall and into said shank portion and co-acting with a threaded bushing in said shank portion to extend said foot member from said leg member to take up the slack in said stocking.

7. In a stretching and drying device for stockings; a two-part form including a foot member having a shank and a leg member including a sleeve portion telescoped over said shank and an end wall; a pair of spring urged clamps pivoted in said end wall and adapted to yieldingly em-

brace the sides of said sleeve portion so as to clamp thereagainst the open end portion of a sock that has been drawn over said form; and a screwjack for extending said foot member from said leg member so as to take up the slack in said stocking, said screwjack comprising a threaded shaft journalled in said end wall and projecting therethrough, a threaded bushing mounted in the end of said shank and threaded upon said shaft; and a handle attached to the projecting end of said shaft and disposed at the end of said leg member.

8. A stretching and drying device as defined in claim 6, including a split bushing mounted in an opening in said end wall and having an internal annular channel receiving a radial flange that is formed integrally on said shaft.

9. In a stretching and drying device for stockings, a two-part form including a foot member having a shank and a leg member including a sleeve portion telescoped over said shank and an end wall portion, said leg member and foot member having central rib portions extending longitudinally thereof and web portions projecting laterally on either side of said central rib portion; means carried by the end of said leg member remote from said foot member for clamping thereto the open end of a sock that has been drawn over said form; and screwjack means extending longitudinally through the central rib portion of the shank part of said foot member and forming a connection between said foot and leg members for extending said foot member from said leg member to take up the slack in said stocking.

10. A stretching and drying device as defined in claim 9, wherein said sleeve portion of the leg member tapers to a relatively thin edge at its end adjacent said foot member, whereby to substantially blend the surface of said leg member with that of said foot member.

11. In a stretching and drying device for stockings, the combination of: a two-part form including a foot member and a leg member extensibly connected together; means for clamping the open end of a stocking drawn over said form, to the end of said leg member remote from said foot member, said last means comprising a pair of yokes having central portions adapted to bear against the sides of said leg member and having end trunnions extending inwardly; sockets in said leg member into which said trunnions are extended; and spring means in said sockets and co-acting with said trunnions to urge said yokes into engagement with said leg member.

12. In a stretching and drying device for stockings, a form over which the stocking may be slipped; and a plurality of spring clamps for clamping the open end of the stocking to said form, said clamps being yoke shaped, having end trunnions pivoted to said form, having intermediate jaw portions for engaging the sock against the form, and having side arms connecting said jaw portion to said trunnions and adapted to function as handles for manipulating the clamps; and spring means acting between an adjacent pair of trunnions of the respective clamps, adapted to yieldingly apply clamping pressure to said jaws in the closed position of the clamps and to hold the yokes in an open position when they have been moved to the open position.

BRUCE A. GEAR.
